UNITED STATES PATENT OFFICE.

OSCAR B. BACH, OF NEW YORK, N. Y.

DESIGN FOR AN UPRIGHT FOR AN ANDIRON.

Application filed December 11, 1926 Serial No. 20,021. Term of patent 3½ years.

To all whom it may concern:

Be it known that I, OSCAR B. BACH, a citizen of the United States, residing at New York city, in the county of New York and State of New York, have invented a new, original, and ornamental Design for an Upright for an Andiron, of which the following is a specification, reference being had to the accompanying drawing, forming part

thereof, in which the figure is a view of the article, slightly in perspective, showing my new design, a conventional form of support being shown in dotted lines.

I claim:

The ornamental design for an upright for an andiron as shown.

OSCAR B. BACH.
